UNITED STATES PATENT OFFICE.

GEORGE E. KELLY AND GEORGE F. ROYER, OF WILKES-BARRE, PENNSYLVANIA,
ASSIGNORS TO THE KELLY-ARNOLD MANUFACTURING CO., OF WILKES-BARRE,
PENNSYLVANIA, A CORPORATION OF PENNSYLVANIA.

TRAIN-PIPE COUPLING.

1,137,406.

Specification of Letters Patent. Patented Apr. 27, 1915.

Original application filed March 5, 1909, Serial No. 481,258. Divided and this application filed August 30, 1909. Serial No. 515,300.

To all whom it may concern:

Be it known that we, GEORGE E. KELLY and GEORGE F. ROYER, citizens of the United States, and residents of Wilkes-Barre, in the 5 county of Luzerne and State of Pennsylvania, have invented certain new and useful Improvements in Train-Pipe Couplings, of which the following is a specification.

This invention relates to improvements in 10 train pipe couplings and particularly to the coupling head and its gasket.

The objects of this invention are to simplify the construction of the coupler head and to provide a novel form of gasket and 15 holding means therefor.

In the drawings: Figure 1 is a bottom view of the coupler; Fig. 2 is a sectional view on the line 2—2 Fig. 1; Fig. 3 is a detail view of the bushing or sleeve, gasket 20 and interlocking means employed within one of the ports of the coupling head; Fig. 4 is a section on the line 4—4 of Fig. 2.

Referring to the drawings 3, 3, designate 25 stems of a train pipe coupling which are connected to the cars in the manner shown in our copending application Serial No. 481,258, filed March 5, 1909, and matured into patent #983,239, dated January 31, 1911, of which this application is a division.

Since the abutting couplers of the cars are 30 similar in construction only one of said couplers will be described. A coupler head 3' is mounted on the stem 3 and provided with a tapped hole 14 to receive a connection to the train pipe. The head is provided 35 with ports 16, 17. A hose-coupling pipe 18 is connected to the head 3' and is adapted to be engaged by the ordinary hose-coupling or fluid pressure brake apparatus.

A valve 19 supported by an arm 20 on a 40 rock shaft 21 mounted in bearings on the coupler head is normally held by the action of the spring 22 in the position in which it closes the outlet or port 17. One end of the 45 spring 22 bears against the pipe 18 and the other is attached to the rock-shaft 21. At an intermediate point in its length this spring extends across an arm or finger 23 which is loosely mounted on the rock-shaft 21 and projects therefrom in such position 50 that it will be engaged by a projection or member on a coöperating coupling head as

the two heads are brought together for the purpose of bringing the ports 17 thereof into alinement. This causes a rocking of 55 the shaft 21 and shifts the valve 19 into the dotted position shown in Fig. 2, thus opening the port 17 and closing the port 16 that communicates directly with the hose-coupling pipe 18. The two heads of the coupling being thus related and the ports 16 closed, the brakeman by opening suitable valves brings 60 the train pipes on the two cars into communication with the ports 17.

In case it is necessary to couple a car having 65 a train pipe coupling constructed in accordance with the present invention with a car having merely the ordinary hand hose coupling the latter is engaged by coupling pipe 18 and as a spring holds the valve 19 in 70 position to close the port 17 the train pipes on the two cars will be connected through the port 16 and hose coupling pipe 18 when the valve in the train pipe is open.

In the embodiment of the invention illustrated 75 the coupling head is provided at one side with a funnel-shaped guide 24 and at the opposite side with a pin mounted on an arm 25 and adapted to coöperate with a funnel guide 24 on the opposite head, and the 80 finger or arm 23 on the valve actuating rock shaft 21 extends across the aperture or opening formed at the reduced end of the funnel-shaped guide members. Therefore when the two coupling heads are brought together the 85 pins on the arms 25 will each move the arms or fingers 23 of the other and thereby automatically shift the two valves 19 away from their nominal position across the port 17 and cause the valves to close the port 16. 90

The above construction thus briefly described is illustrated and described at length in our patent referred to and does not form the subject matter of the present invention.

As shown a suitable bushing 26 is secured 95 within the port 16 of the coupling head and adjacent the outer end thereof is formed a concave seat into which is fitted a gasket 27 of soft rubber and which is circular in cross section. The inner seat for the gasket 27 is 100 formed partly by a groove in the inner face of the bushing 26 and partly by a ring 28 which is arranged in a groove 29 in the bushing, and through the gasket extends a sleeve

30 the inward movement of which is limited by a shoulder 31 within the bushing. The sleeve 30 is provided with a flange portion adapted to engage the gasket 27 and hold the latter on its seat.

5 A bowed spring or locking member 32 is adapted to retain the sleeve within the bushing while permitting a limited movement thereof longitudinally. The length of the 10 spring locking member 32 is greater than the diameter of the sleeve 30 extending around the interior of the sleeve over more than one-half, but over less than three-fourths of the interior circumference of the 15 sleeve and in order that the latter may be introduced into the bushing said locking member is turned into the position indicated in Fig. 3, in which position its ends will lie substantially flush with the outer 20 surface of the sleeve. After the sleeve has been inserted in the bushing a slight pressure on the body of the locking member 32 will shift it into the position indicated in Fig. 2 where it extends directly transverse 25 of the diameter of the sleeve and thereby the bent ends thereof will be projected through apertures in the sleeve 30 and into a groove 33 formed in the bushing. The length of the spring locking member 32 is 30 such that when in place it extends around more than half of the circumference of the sleeve 30 and bears against the interior surface of the latter. By spacing the apertures in the sleeve so that they are not diametrical 35ly opposite one another, the ends of the spring 32 which extend through the sleeve and lock the latter in the groove 33 will be automatically withdrawn from the apertures when the spring 32 is shifted from its 40 transverse position as is shown in Figs. 3 and 4. By exerting a slight pull on the portion of the locking device 32 within the sleeve it may be shifted into the inclined position indicated in Fig. 3, thereby without 45 drawing its ends from engagement with the bushing and permitting the sleeve to be withdrawn and the gasket released.

It will be seen that the locking member 32 does not completely fill the groove 33 and 50 that there is a slight space between the adjacent walls of the sleeve and bushing. When the coupler is in use, that is when the two coupling heads are brought together as shown in Fig. 2 with the port 17 in alignment, the pressure of the fluid within the 55 coupling heads acts against the rings 28 and through them against the gaskets 27 which are thus held in close contact with the bushing and sleeve and in contact with each 60 other. Since the gasket 27 is constructed of soft rubber it may lie entirely back of the metal surfaces at the contact faces of the coupling heads when the couplers do not form an operative connection. In addition 65 the soft rubber construction has the ad-

vantage that the gasket is not broken due to the sudden jar occasioned by the coming together of two coupling heads.

It is obvious that various changes may be made in the details of construction without departing from this invention and it is therefore to be understood that this invention is not to be limited to the specific construction shown and described.

Having thus described the invention, what 75 is claimed is:

1. In a coupler, the combination of a coupler head having a groove adjacent the mouth of a port therein, said groove forming a curved gasket seat, a gasket substantially circular in cross section seated in said gasket seat, a sleeve separate from the said gasket and head extending into said port said sleeve being provided with a flange at one end adapted to fit the curved surface of 80 the gasket and hold the gasket to its seat, and means independent of and located near the inner end of said sleeve for detachably connecting the sleeve to the head.

2. In a coupler, the combination with a 90 coupler head having a groove, of a sleeve loosely mounted within the head, a loose ring on the sleeve, said groove, sleeve and ring forming a gasket seat, a gasket for the seat, a passageway between the head and 95 sleeve, and releasable means for loosely holding the sleeve within the head.

3. In a coupler, the combination with a coupler head provided with a groove, of a sleeve within the head, a loose ring on the 100 sleeve, said groove, sleeve and ring forming a seat of substantially circular cross section, a gasket of substantially circular cross section located in the seat and an annular passage between the head and sleeve.

4. In a coupler, the combination with a coupler head having a groove adjacent the mouth of a port therein, said groove forming a gasket seat, of a sleeve separate from the gasket and head and fitting loosely within 110 said port, said sleeve having a flange at its outer end near the mouth of the port adapted to fit the surface of the gasket and coöperate with the gasket to hold it against its seat, and a movable expansible locking device bearing against the inner surface of the sleeve near the inner end of the latter adapted to engage in a recess in the coupler head and hold the sleeve in position therein.

5. In a coupler, the combination with a coupler head, of a gasket seated in a seat formed within the mouth of a port in said head, a sleeve having apertures therein and fitting loosely within said port and adapted to coöperate with the gasket to hold it 120 against said seat, and a movable spring bow having its body bearing against the inner surface of the sleeve and of such length that when adjusted to a position substantially transverse of the axis of the sleeve its ends 130

will be projected through apertures in the sleeve into engagement with the surrounding portion of the coupler head and loosely retain the sleeve within the head.

5 6. In a coupler, the combination with a coupler head, of a valve in the head a bushing within the head and constituting a seat for the valve, a sleeve within the bushing, a ring on the sleeve, said bushing, sleeve and 10 ring forming a gasket seat and a gasket for the seat.

7. In a coupler, the combination with a coupler head having a port of a valve within the head nominally closing the port a 15 bushing seated in said head and constituting a seat for said valve, a sleeve within the bushing, a ring, said bushing, ring and sleeve providing a gasket seat and a gasket for said seat.

20 8. In a coupler, the combination with a coupler head, of a bushing within a port in said head, said bushing having a shoulder thereon and a groove therein, a gasket seated in a seat formed in the bushing, a sleeve having a flanged portion adapted to engage the gasket and hold the latter on its seat, said sleeve extending into the head and limited in its inward movement by the shoulder on said bushing, and a locking member adapted to 25 retain the sleeve within the bushing and permit a limited longitudinal movement of said sleeve, the ends of said locking member projecting through the sleeve into said groove in the bushing.

30 9. In a coupler, the combination with a coupler head having a port, of a valve within the head normally closing the port, means on the head constituting a valve seat, a recess on said means forming a gasket seat, a 35 gasket for the seat, and a sleeve within the head adapted to engage the gasket and hold the latter on its seat.

40 10. In a coupler, the combination with a coupler head having a port, of a valve with-

in the head normally closing the port, a 45 bushing seated in the port, one end of said bushing constituting a seat for said valve and the opposite end having a groove therein forming a gasket seat, a gasket seated in said seat and a sleeve fitting in the bushing 50 and coöperating with the gasket and bushing to hold the gasket to its seat, and means detachably connecting the sleeve and bushing.

11. In a coupler, the combination with a 55 coupler head having two ports, of a valve in the head arranged to close either port, means extending into the head and affording a seat for said valve near its inner end and a seat for a gasket near its outer end, a 60 gasket seated in the gasket seat and means for holding the gasket to its seat on said first named means.

12. In a coupler, the combination with a coupler head having a port, of a pivoted 65 valve in the head arranged to close the port, a bushing extending into the head and affording a seat for said valve at its inner end and a seat for a gasket at its outer end, a 70 gasket seated in said seat, a sleeve having a flange at one end for holding said gasket to its seat and means for connecting the sleeve to the bushing.

13. In a device of the class described, the combination of a head having two ports 75 therein, a valve capable of closing either port and a bushing fitting one of the ports, said bushing having a gasket seat formed at one end and the opposite end thereof constituting a seat for said valve.

80 In testimony whereof we affix our signature in presence of two witnesses.
